DECORATIVE PANEL FOR CONSTRUCTION PURPOSES

Ronald C. Thedford, P.O. Box 14642,
Oklahoma City, Okla. 73114

Filed Mar. 16, 1967, Ser. No. 6,254

Term of patent 14 years

(Cl. D54—2)

FIGURE 1 is a front elevation view of a decorative panel showing my new design.

FIGURE 2 is a sectional view taken along line 2—2 of FIGURE 1.

FIGURE 3 is a sectional view taken along line 3—3 of FIGURE 4.

FIGURE 4 is an elevational view of the decorative panel shown in FIGURE 1, but showing the panel as it appears when viewed from behind.

I claim:

The ornamental design for a decorative panel for construction purposes, substantially as shown.
